UNITED STATES PATENT OFFICE.

EDMUND HAWTHORNE MICKLEWOOD, OF DEVON, ENGLAND.

VALVE-OPERATING MECHANISM.

1,210,343.

Specification of Letters Patent. Patented Dec. 26, 1916.

Application filed January 30, 1912. Serial No. 674,304.

To all whom it may concern:

Be it known that I, EDMUND HAWTHORNE MICKLEWOOD, a subject of the King of Great Britain, residing in Devon, England, and whose post-office address is 5 St. Michael's Terrace, Plymouth, in the county of Devon, England, consulting engineer, have invented certain new and useful Improvements in Valve-Operating Mechanism, of which the following is a specification.

This invention relates to mechanism for operating a rotary valve controlling the admission and discharge of the working fluid of engines and particularly of an internal combustion engine, which mechanism is adapted to turn the valve rapidly with intermediate periods during which the valve is at rest or comparatively at rest and which enables a complete cycle of opening and closing of the valve to be divided into unequal periods of action.

The invention is illustrated in the accompanying drawing, wherein—

Figure 1 represents a section through a rotary valve assembled in a seating associated with the working cylinder of an engine, the improved valve-operating mechanism being shown applied to the rotary valve, and Fig. 2 is a face view of the improved valve-operating mechanism as viewed from the left in Fig. 1.

The improved valve operating mechanism comprises a stationary cylindrical boss *a* on which is mounted a disk or wheel *f* which can be turned by any suitable means.

From the face of wheel *f* extends a pin *d* which engages in a longitudinal slot *b* in a bar or block *b* which is rigidly secured to the spindle *s* of the rotary valve *l*. The valve *l* is mounted in its seating *e* fixed to the wall *c* of the working cylinder of the engine and is shown controlling the intake and exhaust ports or passages *p*, *p'*, respectively, the valve having a port *p²* therein which alternately establishes communication between the ports *p* and *p'* and the explosion chamber *O* above the engine piston *P*. The spindle *s* is journaled in the boss *a* in eccentric relation therewith.

Owing to the relative position of the axis 50 of the wheel *f* and the valve spindle *s* not being co-axial, the bar *b*, when wheel *f* is rotated at uniform speed, is driven by pin *d* and has imparted to it a variable rotary speed which is transmitted to the valve 55 spindle *s* and valve *l*. The latter can thus be arranged to make a longer dwell over one part of a complete turn than over the other portion thereof, for the extent of variation of the movement of the valve is governed by 60 the eccentricity of its axis with respect to the axis of the wheel *f*.

Having thus described my invention and the best means I know of carrying the same into practical effect, I claim:—

1. The combination of a rotary port-controlling valve, and means adapted to impart a variable rotary speed to the valve, said means consisting of a stationary cylindrical boss carried by the engine, a spindle operatively connected with the valve and journaled in the boss in eccentric relation with the axis thereof, a revoluble member mounted co-axially on the boss, a rotary member secured to the spindle, a driving connection 70 between the said two members, and means for driving the first said member.

2. The combination of a rotary port-controlling valve, and means adapted to impart a variable rotary speed to the valve, said 80 means consisting of a stationary cylindrical boss carried by the engine, a spindle operatively connected with the valve and journaled in the boss in eccentric relation with the axis thereof, a revoluble member mounted co-axially on the boss, a rotary member secured to the spindle, a driving connection 85 between the said two members, comprising a pin on the revoluble member slidably engaging a slot in said rotary member, and 90 means for driving the first said member.

In testimony whereof I have signed my name to this specification in the presence of two subscribing witnesses.

EDMUND HAWTHORNE MICKLEWOOD.
